INVENTOR

BY
Marie Spangler
ATTORNEY

UNITED STATES PATENT OFFICE.

SAMUEL BERGER, OF NEWARK, NEW JERSEY.

DOLL CONSTRUCTION.

Application filed April 17, 1926. Serial No. 102,637.

This invention relates to dolls and more particularly is directed to an improved construction of a doll body for supporting a limb animating mechanism and head.

5 Among the objects of the invention is to provide an improved doll body construction of the character described comprising a simple structure which is cheap to manufacture, permits easy and quick assembly of the doll 10 parts and practical and efficient to a high degree.

Other objects of this invention will in part be obvious and in part hereinafter pointed out.

15 The invention accordingly consists in the features of construction, combinations of elements and arrangement of parts which will be exemplified in the construction hereinafter described and of which the scope of 20 application will be indicated in the following claims.

In the accompanying drawing, in which is shown one of the various possible illustrative embodiments of this invention,

25 Fig. 1 is a perspective view of a walking doll embodying the invention.

Fig. 2 is a side elevational view of an undressed doll, portions thereof being broken away to show the construction of the body.

30 Fig. 3 is a plan view of a blank for forming the improved body of the doll.

Referring in detail to the drawing, 10 denotes a walking-doll embodying the invention. Said doll is seen to comprise a tubular body or casing 11 in which is mounted a limb actuating mechanism 12 for animating the legs 13 which extend from the lower end 11^a of said casing and the arms 14 which are suitably connected with said mechanism through 35 openings 11^e, one of which is embodied in the perforation 11^f in the blank 111 and the other formed by the coaction of cut-outs 11^g in said blank.

The animating mechanism 12 may be of 45 any well known construction, and is not shown here in detail as it forms no part of this invention, said mechanism being secured to the casing 11 in any suitable manner as by tabs 12^b which project through holes 11^b in said casing. For winding the mechanism the usual winding key 15 is provided which extends through a slot 11^c in said casing.

See Figs. 2 and 3.

The body or casing 11 is preferably 50 formed of a blank stamped from a single sheet of material 111, said sheet being shaped

and bent to form the tubular body structure shown in Fig. 2. Said structure may be retained in tubular shape by any suitable means such as integrally formed tabs 11^d 60 extending from opposite edges of said sheet, said tabs forming a quick-detachable fastening with the slotted washers 16. The top and bottom ends of said tubular structure are formed with upper and lower grooved or beaded edges 17 and 18 respectively. The upper beaded edge is adapted to engage a flanged neck rim 19^a formed on the doll head 19 as shown in Fig. 2 and the lower beaded edge 18 to retain the underclothes 70 20 of the doll from slipping off the body 11, (see Fig. 1.) Said blank sheet 111 may also be provided with aligned slots or perforations 111^a extending vertically through the middle portion thereof to facilitate bending 75 the said sheet into the tubular shape.

In assembling the doll 10, the sheet 111 is bent into tubular shape and the animating mechanism 12 with the limbs attached thereto is mounted in place by securing the tabs 12^b in the openings 111^a. The flanged rim 19^a of the head is then positioned to be engaged by the upper beaded edge 17 and the tabs 11^d secured by means of the washers 16 for retaining the body 11 in shape and for clamping the head 19 to said body. The doll may now be dressed, the underclothes 20 being held to the body 11 by securing same above the beaded edge 18. The above described construction of the 90 body 11 is thus seen to form a simple structure having means whereby both the animating mechanism, limbs, head, and dress are easily and quickly assembled to form the complete doll.

95 It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters 110 Patent:—

1. In a doll construction, a head having

a flanged neck portion, and a tubular body formed of sheet material having one end thereof formed with a beaded edge, said edge being adapted to engage with said 5 flanged neck portion for mounting the head in position.

2. In a doll construction of the character described, comprising a doll head, a tubular body formed of sheet material having 10 beaded edge portions, one beaded portion comprising means for securing said head in position and another bead comprising means to retain clothes for said doll on said body.

3. A doll construction of the character 15 described, comprising a head and limbs, a limb animating mechanism, a body for mounting said head and mechanism, said

body comprising a tubular structure formed of a single sheet of material, means at one end of said structure for engaging said head, and means for retaining said body portion in tubular shape, said latter means serving to retain the first mentioned means in effective engagement with said head.

4. In a doll construction of the character 25 described, a blank sheet cut and bent to form a tubular body, a head, a bead formed at one end of said body for mounting said head in position, and means for retaining said body in tubular shape, said means being 30 effective for rigidly retaining said bead in engagement with the head.

In testimony whereof I affix my signature.
SAMUEL BERGER.
